UNITED STATES PATENT OFFICE

JOSEPH L. SWEET, OF ATTLEBOROUGH, MASSACHUSETTS, ASSIGNOR TO
R. F. SIMMONS & CO., OF SAME PLACE.

DESIGN FOR A CIGAR-CUTTER CASE.

SPECIFICATION forming part of Design No. 23,028, dated January 30, 1894.

Application filed May 9, 1893. Serial No. 473,600. Term of patent 3½ years.

To all whom it may concern:

Be it known that I, JOSEPH L. SWEET, of Attleborough, Massachusetts, have invented a new and original Design for a Cigar-Cutter Case, of which the following is a specification.

I will fully describe the cigar-cutter case embodying my design, and then point out the novel features in a claim.

In the accompanying drawings, Figure 1 is a side view of a cigar cutter, embodying the design. Fig. 2 is an edge view of the same.

Similar letters of reference designate corresponding parts in both figures.

Both sides of the cigar cutter case are alike. It will be seen that the sides of the cutter case are convexly curved at one end and that they taper from that end with a concave curve

or near to the other end. A representation of a bust of Columbus is delineated near one end. At the sides, and above the bust are 20 foliate figures. Below the bust is another foliate figure.

What I claim, and desire to secure by Letters Patent, is—

The design for a cigar-cutter case, substantially as shown and described.

In testimony whereof I have signed my name to this specification in the presence of two subscribing witnesses.

JOSEPH L. SWEET.
